AUTOMATIC IRONING SHOE RESET

John A. Castricone, Peoria, Ill., assignor to
 Altorfer Brothers Company, Peoria, Ill., a corporation of Illinois

Application May 16, 1938, Serial No. 208,137

10 Claims.

(Cl. 38—61)

This invention relates to ironing machines and more particularly to an automatic ironing shoe reset mechanism. In the conventional ironer construction, it is customary to provide an ironing bed and shoe between which the work is passed during the ironing operation. These elements are subject to numerous variations, but as a rule the ironing bed is of cylindrical or somewhat arcuate shape and is provided with a fabric surface and suitable padding in a manner well understood in the art. In power driven machines this bed is usually caused to revolve or oscillate in relationship to a heated ironing shoe shaped to conform with the surface of the ironing bed and movable into and out of engagement therewith. It is customary to employ power driven means for causing the ironing bed and shoe to engage and disengage, and ordinarily this power engaging means is synchronized with the roll driving means in such a manner that as the ironer bed begins to move, the bed and shoe are caused to engage, while as the bed ceases its movement, the bed and shoe disengage.

It is also quite customary to provide such mechanisms with an emergency release control and spring retracting means, whereby the ironing elements may be instantaneously disengaged irrespective of the power driving mechanism. The necessity for such an emergency release mechanism will be readily appreciated when it is considered that these ironers are usually supplied with power through the ordinary household cord and plug which may be easily damaged or disengaged in such a manner as to cause a power failure.

It should be pointed out that since the power driving means is utilized both to engage and disengage the ironing elements any power failure while the ironing elements are in engagement will leave the highly heated ironing shoe in engagement with the work and also in engagement with the fabric surface of the ironing bed, and that if this condition is allowed to continue for more than a very few seconds, the heat of the shoe will scorch or burn both the work being ironed and the fabric surface of the bed. Such an emergency release construction, however, necessarily requires that some means be provided for resetting the parts in their operative positions. This has heretofore been accomplished by manually resetting the ironing elements either by means of a manual resetting control or by manually moving the elements themselves. This is disadvantageous in that if the operator is required to manually move one of the ironing elements,

she is in immediate danger of being severely burned by contact with the heated ironing shoe, while if a separate reset control handle is provided, the cost of the unit is increased and in addition the presence of an unsightly control lever increases the size and complicates the operation of the machine. It should also be pointed out that in perhaps the majority of cases the operator is entirely unfamiliar with the internal mechanism of the ironer and having never been instructed as to the proper manner of resetting the ironing elements, will believe that the machine is out of order.

It is, therefore, a primary object of this invention to provide an ironing machine with an emergency release mechanism of such design and construction that the ironing elements may be automatically reengaged in normal operating relationship after release.

Another important object of the invention is to provide a power driven ironing machine with a manual release mechanism of such design and construction that operation of the manual release will be effective to disengage and separate the cooperating ironing elements irrespective of the operation of the power driving means associated therewith but in which normal operation of such power driving mechanism subsequent to the manual release will be effective to reengage the ironing elements in normal operative relationship.

Another object of the invention is to provide a manually operable emergency release mechanism wherein the emergency released position of the ironing elements corresponds with the normal released position of the ironer pressure means and means for automatically engaging the elements with the pressure means as they reach these positions.

A further object of the invention is to provide a power driven ironer with an emergency release effective to separate the ironing elements to their normal released position and a secondary release means allowing the ironer elements to separate to a greater spaced relationship in order to facilitate cleaning or polishing of the ironer shoe.

Another object of the invention is to provide an automatic ironer release mechanism which is simple in construction, rugged in operation and economical in manufacture.

50 Referring now to the drawings:

Fig. 1 is a front elevation of an ironing machine constructed in accordance with the principles of this invention;

Fig. 2 is an end elevation of the machine illustrated in Fig. 1;

Fig. 3 is an enlarged fragmental end elevation of the ironing elements and power driving mechanism with certain parts being broken away to more clearly illustrate the ironing element pressure means.

Fig. 4 is a transverse detailed sectional view taken substantially on the plane of the line 4—4 in Fig. 1.

Fig. 5 is a rear elevation of the ironer driving means, certain parts thereof being shown in section.

Fig. 6 is a detailed sectional view of the ironer release mechanism, the parts thereof being shown in an emergency released position.

Fig. 7 is a detailed sectional view similar to Fig. 6, the parts being shown in their normal released position.

Fig. 8 is a detailed sectional view similar to Fig. 7, the parts being shown in their normal operating position.

The ironing bed 11 is here illustrated in the form of a cylinder or roll, mounted for rotation on a bracket 12 which may be cast integrally with a gear housing 13 and supported in any desirable manner upon the ironer frame 15. A driving motor 16 is bolted on the gear housing 13 and serves to rotate or oscillate the ironing bed 11 through the medium of a suitable gearing (not shown) housed within the housing 13.

The motor operation of the ironer is controlled by control lever 17 pivotally mounted on the pin 18 and connected with the control shaft 19 journaled in the wall of the gear housing 13 by means of a control rod 21. The arrangement is such that the motor 16 will run continuously while the ironer roll or bed 11 may be engaged or disengaged from driving connection by the actuation of the control lever 17. When the control lever 17 is momentarily depressed, the roll 11 will be engaged and driven by means of the motor 16 until such time as the lever 17 is again depressed in order to disengage the driving connection and stop the roll.

The ironer shoe 31 is pivotally mounted on a pin 32 carried at the upper end of a movable arm 33 pivoted to the standard 34 by means of a pin 35. The shoe 31 includes a concave arcuate ironing surface 36 which is adapted to bear against the similarly shaped surface of the ironing bed 11.

Power actuated pressure engagement between the shoe 31 and the bed 11 is accomplished by mounting an eccentric 41 on a rotatable shaft 42 within the gear case 13 and by operatively connecting the eccentric strap 43 with the movable ironing shoe 31 in such a manner that the shoe 31 will move into and out of engagement with the bed or roll 11 in accordance with the position of the eccentric 41 with respect to the rotating shaft 42. The arrangement is such that whenever the control lever 17 is momentarily depressed and the ironing bed 11 begins to rotate, the shaft 42 will revolve 180° from the position shown and will move the eccentric strap to the right as shown in Fig. 3, thereby causing the movable arm 33 to pivot downwardly about the pin 35 in such a manner as to bring the arcuate surface 36 of the ironing shoe 31 into pressure engagement with the ironing bed 11. When the eccentric 41 has rotated 180° and brought the ironing elements into engagement, an automatic clutch (not shown) disengages the driving connection to the eccentric 41 and the parts remain in engaged position until the operating lever 17 is again actuated. When this is done 75

the driving connection to the ironing bed 11 is disengaged and simultaneously the eccentric 41 is again engaged and rotated 180° back to the normal disengaged position as illustrated in Fig.

5 3. This will, of course, result in moving the eccentric strap 43 back to the left and in allowing this motion to be transmitted to the swinging arm 33 in such a manner as to disengage the shoe 31 from the ironing bed 11 and return the shoe 31 to the normal released position illustrated.

The eccentric strap 43 is provided with a slot 44 in order to engage a pin 45 carried by a crank arm 46 fixedly mounted on an oscillating pressure shaft 47 journaled in bearings 48 formed integrally with the walls of the gear housing 13. A coiled compression spring 49 is carried with a suitable socket in the eccentric strap 43 in order that a certain amount of yielding will be permitted between the ironing elements when they are in engaged position.

Predetermined pressure adjustment between the roll 11 and shoe 31 is accomplished by an arm 51 which is secured to the oscillating pressure shaft 47 by means of a cross pin 52 and which carries an adjustable index plate 53 angularly movable with respect to the arm 51 within the limits prescribed by the adjusting slot 54. This index plate may be clamped in any predetermined angular setting with respect to the arm 51 by means of a cap screw 55. The driving shaft 47 extends beyond the index plate 53 in order to provide a pilot portion 56 freely rotatable within the drilled opening 57 of a driven clutch element 58. A driven oscillating pressure shaft 59 is secured within the drilled opening 57 in axial alignment with the driving pressure shaft 47 but is rigidly connected with the clutch element 58 by a cross pin 61. A spring 40 pressed plunger 62 is slidably mounted in a slide-way 63 in the clutch element 58 and is normally held in locked engagement within a suitable orifice 64 in the index plate 53 by means of a compression spring 65 bearing against a threaded plug 66.

Examination of Figs. 5 and 6 will show that the arrangement is such that the oscillating movement of the pressure shaft 47, as imposed by means of the eccentric 41 and eccentric strap 43, will be transmitted through the pin 52 and arm 51 to the index plate 53 and then through the plunger 62 and driven clutch element 58 in such a manner as to oscillate the driven pressure shaft 59 in accordance with the movement of the driving pressure shaft 47 whenever the plunger 62 is seated within the orifice 64. The degree of pressure to be exerted between the ironing elements is adjustable in accordance with the requirements of the work by adjusting the position of the index plate 53 with respect to the arm 51.

The opposite end of the driven pressure shaft 59 is journaled in a bearing 71 carried by the angle plate 72 secured on the lower surface of the top plate 73 by any desirable means, and is provided with a crank arm 74 rigidly mounted at the extreme end by means of the cross pin 75.

The movement of the driven oscillating pressure shaft 59 is transmitted to the ironer shoe 31 by means of a connecting rod 76 mounted on the crank pin 77 carried by the crank 74 and extending upwardly to the pin 78 secured in bosses 79 within the walls of the swinging arm 33. The shoe 31 is normally urged out of en-

gagement with the roll 11 by a coiled tension spring 81 which extends downwardly from the pivot pin 35 to a cap screw 82 carried by the connecting rod 76. The cap screw 82 also serves to secure an adjustable limit stop member 83 which is slidable along the connecting rod 76 and which may be clamped in any position therealong as limited by the adjusting slot 84. The limit stop 83 includes an upper flange 85 which is adapted to abut the lower surface of a cooperating stop shaft 86 mounted in one of the walls of the standard 34 and rotatable by means of a handle portion 87.

It will be seen from Figs. 4 and 5, that the inner end of this shaft 86 is cut away at 88 in order that the operator may move the shoe 31 from the normal operating position or emergency released position as shown in full lines in Fig. 4, to the second released position, as shown in dotted lines. To accomplish this, the operator will rotate the shaft 86 through approximately one-half of a revolution of movement by means of the handle 87, thus moving the cut-away portion 88 to the lower side of the shaft, and allowing the flange 85 of the limit stop 83 to rise to a correspondingly greater height before engaging the shaft 86.

A manual release control lever 91 is pivotally mounted in a pair of bushings 92 carried within the frame 15 of the ironer and is provided with a crank arm 93 having an orifice 94 therein adapted to receive a reduced end portion 95 of a horizontal lever 96 pivotally mounted on the stud 97. A pull rod 98 is secured to the lever 96 and extends to a yoke 99 suitably pinned to the plunger 62 housed within the driven clutch element 58. The release lever 91 is not ordinarily used in the operation of the machine, but is provided as an emergency release in order to prevent any possibility of damage to the machine or to the work which might be caused by failure of the source of power at a time when the ironing shoe 31 was in contact with the roll 11. It should be understood that the ironing shoe 31 is normally maintained at a relatively high degree of heat, as provided by electrical heating units 101 controlled by the switch 102 and it is, therefore, imperative that the fabric surface 103 of the ironing bed 11 be in motion at all times that the shoe 31 and the fabric 103 are in engagement.

As herein before pointed out, the control mechanism is such that the power drive is utilized not only to move the shoe 31 into engagement with the roll 11, but also to move these ironing elements out of engagement and, therefore, the emergency release lever 91 is provided in order that the ironing elements may be instantly disengaged irrespective of the power drive, or in the event of a power failure. By moving the emergency release lever 91 downwardly, the crank arm 93 carried thereby will move to the right as shown in Fig. 5, thus moving the horizontal lever 96 and causing the pull rod 98 to withdraw the plunger 62 from the orifice 64 in the index plate 53 against the action of the compression spring 65. This movement completely disengages the operating connection between the driving pressure shaft 47 and the driven pressure shaft 59, leaving the shaft 59 free to move under the influence of the tension spring 81 which will act to draw the connecting rod 76 upwardly, thus pivoting the swinging arm 33 about the pin 35 and withdrawing the shoe 31 from engagement with the ironing bed 11. This upward

movement will be limited by means of the limit stop 83 which is so adjusted that the emergency release position of the shoe 31, and, consequently, of the several parts to and including the clutch element 58, will exactly correspond with the normal operating position of these parts when they are released from engagement with the roll 11 by means of the operation of the eccentric 41.

With this adjustment properly made, it will readily be seen that when the power drive is re-established and the eccentric 41 again rotated to the position shown in Fig. 3, the shaft 47 will oscillate to bring the orifice 64 of the index plate 53 into registry with the plunger 62. As the index plate 53 moves into registering position with the plunger 62, the compression spring 65 will snap the plunger into the orifice 64 and automatically reset the machine for further operation by re-establishing the pressure drive between the eccentric 41 and the ironer shoe 31.

As hereinbefore pointed out, the normal stroke of the eccentric 41 is sufficient to move the crank 46 through the arc of the angle A, (see Fig. 3) but in order that the ironing elements shall engage under a resilient force rather than under a positive mechanical drive, the spring 44 is compressed during the latter part of the movement of the eccentric strap 43 and the actual oscillating movement of the shaft 47 is therefore represented by the angle A'. The relationship between the angles A and A' will also vary in accordance with the thickness of the work being ironed, but in any event it will be noted that when the eccentric 41 moves to the position shown, the pin 45 will always return to a position exactly upon the line X. Similarly, the cap screw 55 carried by the arm 51 at the opposite end of the shaft 47 will always return to exactly the same released position, which is also indicated by the line X in Fig. 6.

However, since the index plate 53 is adjustable with respect to the arm 51 within the limits prescribed by the adjusting slot 54, the arc through which the center of the orifice 64 will move may be represented by the angle B when the machine is adjusted for maximum pressure or by the angle B' when adjusted for minimum pressure. This means that the full released position of the center of the orifice 64 may lie at any point within the angle C, according to the adjustment of the index plate 53. (See Fig. 6.)

As hereinbefore pointed out, in order to accomplish an automatic resetting of the machine, the angular positions of the orifice 64 and of the plunger 62 must at some time correspond in order that the compression spring 63 may snap the plunger 62 into engagement. This is accomplished in the released position of the parts in the present instance by providing the adjustable limit stop 83 with an adjustment slot 84 of sufficient length that the emergency released position of the center line of the clutch element 58 and plunger 62 may be adjusted to any point within the angle D, which should be large enough to include the angle C. Therefore, whenever the pressure adjustment is altered by varying the angular relationship between the arm 51 and the index plate 53 the limit stop 83 may be correspondingly adjusted in order that the plunger 62 and orifice 64 will come into exact longitudinal alignment whenever the shoe 31 is in its emergency released position and the eccentric 41 operates to move the oscillating shaft 47 to its normal released position.

At certain times it is desirable to separate the

ironing elements a considerably greater distance in order that the concave ironing face 38 of the ironing shoe 31 may be cleaned or polished. This movement is allowed as hereinbefore pointed out by moving the control handle 87 into such position that the cutaway portion 88 of the shaft 86 is positioned on the lower half of the shaft in such a manner as to allow the limit stop 83 to rise to a greater height than the emergency released position. It will be understood, of course, that rotation of the handle 87 back to the position illustrated in the drawings will exert a camming action upon the flange 85 of the limit stop 83 and will thus move the ironing shoe 31 from the dotted line position back to the full line position as illustrated in Fig. 4.

In the normal operation of the machine the operator will first place the work to be ironed in position on the ironer roll 11 and will then actuate the knee control 17 to start the rotary movement of the roll 11 and to cause the ironing shoe 31 to move into pressure engagement with the work positioned on the roll 11. This is accomplished by means of the control rod 21 which extends between the knee control lever 17 and the control shaft 19 journaled in the wall of the gear housing 13. The movement of the control shaft 19 will actuate suitable clutch mechanisms housed within the gear box 13 to rotate the eccentric 41 through 180° of movement from the position shown in the drawings and thus move the eccentric strap 43 to the right, as viewed in Fig. 3, in such a manner as to oscillate the driving oscillating shaft 47 and draw the swinging arm 33 downwardly by means of the connecting rod 76 and crank 74 to force the ironing shoe 31 into pressure engagement with the roll 11.

The ironing shoe 31 will remain in pressure engagement with the rotating roll 11 until the knee control 17 is again actuated, at which time an automatic clutch mechanism housed within the gear box 13 will again rotate the eccentric 41 through 180° of movement to return the parts to the position shown in Fig. 3 to disengage the shoe 31 from the roll 11 and stop the rotary movement of the roll 11. The details of the mechanism within the gear box 13 by which this action is accomplished, have not been described in the present application since it forms no essential part of the invention and since it has been fully described in the United States Patent No. 2,115,941, issued to this applicant on May 3, 1938.

In view of the complete description of this mechanism set out in the specification of said patent, detailed description in this application is not considered to be necessary, but it should be pointed out that the mechanism provides a power operated means for moving the ironer elements 11 and 33 into cooperating pressure engagement and a power operated means to release these elements from engagement and move them into spaced relationship with each other. Both of these functions are accomplished by power transmitted through the gear box 13 from the motor 16, and the knee control lever 17, control rod 21, and control shaft 19 merely serve as manual actuating means whereby the power operated mechanism may be caused to operate according to the will of the operator.

The emergency release and reset mechanism which constitutes the principal novelty of this invention is controlled by the manual release control lever 91. Manual operation of this lever 91 will cause it to pivot in the bushings 92 to

move the crank arm 93 and lever 96 in such a manner as to cause the pull rod 98 to withdraw the plunger 62 from the index plate 53. As hereinbefore pointed out, this operation will break the operative connection between the power operated pressure mechanism exemplified by the eccentric 41 and the separable ironer elements 11 and 31 and will allow the tension spring 81 to contract and urge the ironing shoe 31 out of engagement with the ironing roll 11 and into the predetermined release position established by the adjustable limit stop 83 and the stop shaft 86. It will be readily understood that since the limit stop 83 and the connecting rod 76 are mechanically connected with the driven element 58, the spring pressed plunger 62 will be caused to move to a predetermined release position governed by the adjustment of the adjustable limit stop 83.

The relative positions of the roll 11 and shoe 31 are now exactly the same as though the shoe 31 had been withdrawn from the roll by means of the power operated release mechanism exemplified by the eccentric 41, but this emergency release mechanism operates entirely independently of any power operated devices and is, therefore, adapted to release the shoe 31 from the roll 11 at all times. This provides important advantages over any type of power operated release mechanism since it will be unfailing in operation even though the power circuit to the driving motor may have been accidentally interrupted at a time when the highly heated ironing shoe 31 is in engagement with delicate fabrics which would be scorched and damaged if allowed to remain in contact with the shoe 31 for an interval of time longer than a very few seconds.

To reset the emergency release mechanism the operator need only actuate the knee control lever 17 which will operate through the eccentric 41, as hereinbefore pointed out, to swing the driving element 51 into its normal released position. When this is done the driving element 51 and driven element 58 will be in corresponding angular alignment and the compression spring 65 will snap the plunger 62 into the orifice 64 in the index plate 53 to interlock the driving element 51 and the driven element 58 and re-establish the operative connection between the power operated pressure devices exemplified by the eccentric 41 and the ironing elements 11 and 31.

While I have shown and described a preferred embodiment of this invention as required by the patent statutes, I am aware that it is subject to numerous modifications without departing from the invention spirit and I, therefore, do not wish to be limited except as by the scope of the appended claims.

I claim:

1. In an ironing machine, an ironer bed comprising a rotatably mounted fabric surfaced cylindrical roll, and means for supporting said roll; an ironer shoe including an electrically heated concave ironing surface adapted to engage said fabric surface of said ironer bed, and means for supporting said shoe including a swinging arm; power means including a motor, a clutch, and reduction gearing for rotatably driving said ironer bed with relation to said ironer shoe; power pressure means for moving said shoe and roll into and out of engagement, said pressure means including an oscillating driving shaft with an eccentric and crank for imparting oscillating movement thereto, an oscillating driven shaft, a disengageable clutch element operatively connecting said driving and

driven shafts, a crank on said driven oscillating shaft, and a connecting rod extending from said crank to aforesaid swinging arm; a manually operable emergency pressure release including mechanism effective to disengage aforesaid oscillating shaft clutch and spring means urging said ironer shoe out of engagement with said ironer roll; and automatic pressure reset means including an adjustable release limit stop whereby the emergency released position of the driven clutch elements may be adjusted to correspond to the normal released position of the driving parts, and spring actuated means adapted to re-establish the driving connection between said driving and driven clutch elements.

2. In an ironing machine, an ironer bed; an ironer shoe; power means for relatively driving said ironer bed and shoe; power pressure means for moving said shoe and roll into and out of engagement, said pressure means including an oscillating driving shaft with an eccentric and crank for imparting oscillating movement thereto, an oscillating driven shaft, a disengageable clutch element operatively connecting said driving and driven shafts, a crank on said driven oscillating shaft, and power transmission means extending from said crank to aforesaid ironer shoe; a manually operable emergency pressure release including mechanism effective to disengage aforesaid oscillating shaft clutch, and spring means urging said ironer shoe out of engagement with said ironer roll; and automatic pressure reset means including an adjustable release limit stop whereby the emergency released position of the driven clutch elements may be adjusted to correspond to the normal released position of the driving parts, and spring actuated means adapted to re-establish the driving connection between said driving and driven clutch elements.

3. In an ironing machine, an ironer bed; an ironer shoe; power means for relatively driving said ironer bed and shoe; manually actuated power pressure means for moving said shoe and roll into and out of engagement, pressure transmission means including a driving shaft, a driven shaft, a disengageable clutch element operatively connecting said driving and driven shafts, and adjusting means effective to vary the normal relative positions of said driving and driven shafts, manually operable emergency pressure release means effective to release aforesaid clutch, spring means urging said ironer shoe out of engagement with said ironer roll; and automatic pressure reset means including an adjustable release limit stop whereby the emergency released position of the driven clutch element may be adjusted to correspond to the normal released position of the driving parts, and spring actuated means adapted to re-establish the driving connection between said driving and driven clutch elements.

4. In an ironing machine, an ironer bed comprising a rotatably mounted fabric surfaced cylindrical roll, and means for supporting said roll; an ironer shoe including an electrically heated concave ironing surface adapted to engage said fabric surface of said ironer bed, and means for supporting said shoe including a swinging arm; power means including a motor, a clutch, and reduction gearing for rotatably driving said ironer bed with relationship to said ironer shoe; power pressure means for moving said shoe and roll into and out of engagement, said pressure means including a driving shaft, a driven shaft, a disengageable clutch operatively connecting

5 said driving and driven shafts, a power connection extending from said driven shaft to aforesaid swinging arm; manually operable emergency pressure release means effective to release aforesaid clutch, spring means urging said ironer shoe out of engagement with said ironer roll; and automatic pressure reset means including power driven means responsive to operation of the roll driving mechanism for moving said driving pressure clutch element into engaging relationship with said driven pressure clutch element at its emergency released position, and spring actuated means for reengaging said driving and driven pressure clutch elements.

15 6. In a pressing machine including a plurality of separable pressing elements, power-operated pressure means for moving said elements into pressing relationship and for causing said separable pressure elements to move into spaced relationship with each other, and manual control means whereby said power-operated pressure means may be caused to operate, the combination of means for transmitting pressure from said power-operated pressure means to aforesaid separable pressing elements comprising a driving pressure transmission element movable between a pressure position and a predetermined release position; a driven pressure transmission element movable between a pressure position and a pre-determined release position, means for causing said driving pressure element and said driven pressure element to operatively interlock when both of said elements assume said release position, spring means for moving said driven pressure transmission element to said predetermined release position when said driven pressure transmission element is not interlocked with said driving pressure transmission element, and manually operable mechanism adapted to release said 20 pressure transmission elements from said interlocked relationship.

25 7. In a pressing machine including a plurality of separable pressing elements, power-operated pressure means for moving said elements into pressing relationship and for causing said separable pressure elements to move into spaced relationship with each other, and manual control means whereby said power-operated pressure means may be caused to operate, the combination of means for transmitting pressure from said power-operated pressure means to aforesaid separable pressing elements comprising a driving pressure transmission element movable between a pressure position and a release position; a driven pressure transmission element movable between a pressure position and a release position, means for causing said driving pressure element and said driven pressure element to operatively interlock when both of said elements assume said release position, spring means for moving said driven pressure transmission element to said release position when said driven pressure transmission element is not interlocked with said driving pressure transmission element, and manually operable mechanism adapted to release said pressure transmission elements from said interlocked relationship.

30 8. In a pressing machine, a plurality of separable pressing elements; power operated pressure means associated with said pressing elements whereby said pressure elements may be moved into cooperating relationship with each other, said power operated pressure means comprising a motor, an eccentric driven by said motor and adapted for intermittent movement between a

plurality of predetermined position, means for operatively connecting said eccentric to said separable pressing elements whereby said separable pressing elements will be caused to move into and out of pressure engagement with each other responsive to the movement of said eccentric, manually actuated means whereby said eccentric may be selectively moved to any of said predetermined positions by the driving force exerted by said motor, and an emergency release mechanism comprising a clutch for breaking the operative connection between said eccentric and said separable pressing elements adapted to be released by manual manipulation independently of any of said power operated mechanisms, said clutch comprising a driving element operatively connected with said eccentric and a driven element operatively connected with said separable pressing elements, spring actuated means effective to cause said driving element and said driven element to operatively interlock whenever said elements move into interlocking position, and means responsive to the operation of the aforementioned eccentric to move said driving clutch element and said driven clutch element into said interlocking position.

8. In a pressing machine including a plurality of separable pressing elements and power operated pressure means for moving said separable pressing elements into engagement comprising pressure devices adapted for intermittent rotary movement between a pressure position and a release position, a motor for driving said pressure devices, and manual control means whereby said pressure devices may be moved from either of said positions to the other by the driving force of said motor to provide power operated means for applying pressure between the said separable pressing elements and power operated means for releasing said pressure, the combination of an operative connection including a clutch between said pressure devices and said separable pressing elements, manually operable means for disengaging said clutch to break said operative connection to release said separable pressure elements from said power operated pressure means independently of the operation of said pressure devices, and means responsive to the continued operation of said pressure devices for causing said clutch to reengage to reestablish the operative connection between said pressure devices and said separable pressing elements.

9. In a pressing machine including a plurality of separable pressing elements and power oper-

ated pressure means for moving said separable pressing elements into engagement comprising pressure devices adapted for intermittent rotary movement between a pressure position and a release position, a motor for driving said pressure devices, and manual control means whereby said pressure devices may be moved from either of said positions to the other by the driving force of said motor to provide power operated means for applying pressure between the said separable pressing elements and power operated means for releasing said pressure, the combination of an operative connection between said pressure devices and said separable pressing elements, manually operable means to break said operative connection to release said separable pressure elements from said power operated pressure means independently of the operation of said pressure devices, and means responsive to the continued operation of said pressure devices for causing said clutch to reengage to reestablish the operative connection between said pressure devices and said separable pressing elements.

10. In a pressing machine including a plurality of separable pressing elements and power operated pressure means for moving said separable pressing elements into engagement comprising pressure devices adapted for intermittent rotary movement between a pressure position and a release position, a motor for driving said pressure devices, and manual control means whereby said pressure devices may be moved from either of said positions to the other by the driving force of said motor to provide power operated means for applying pressure between the said separable pressing elements and power operated means for releasing said pressure, the combination of pressure transmission mechanisms interconnecting said power operated pressure means and said separable pressing elements and comprising a driving member, a driven member, means for operatively interlocking said driving member and said driven member when each of said members reaches a predetermined interlocking position, positioning mechanisms including a spring and limit stop to move said driven member to said predetermined interlocking position, means responsive to the operation of said power operated pressure means for moving said driving member to said predetermined interlocking position, and manually operable means to release said driven member from operative relationship with said driving member.
